(57) **CLAIM**

What is claimed is the ornamental design for a writing implement, as shown and described.

DESCRIPTION

FIG. 1 is an isometric view of a writing implement showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines in FIGS. 1-3 are included to show indicia on the writing implement that form no part of the claimed design.
